ROTARY MOWER HOUSING

Sherman C. Heth, Racine, Warren H. Price, South Milwaukee, and Donald W. Doman, Jamesville, Wis., assignors to Jacobsen Manufacturing Company, Racine, Wis., a corporation of Wisconsin

Filed Sept. 24, 1962, Ser. No. 71,814

Term of patent 14 years

(Cl. D40—1)

Fig. 1.

Fig. 2.

Fig. 3.

Fig. 4.

FIGURE 1 is a perspective view, taken generally from the side of a rotary mower housing embodying our new design;

FIGURE 2 is a perspective view taken generally from the front thereof, but on a reduced scale;

FIGURE 3 is a top plan view thereof but on an enlarged scale;

FIGURE 4 is a sectional view taken along line 4-4 in FIGURE 3;

FIGURE 5 is a fragmentary sectional view taken along line 5-5 in FIGURE 3, but on an enlarged scale; and

FIGURE 6 is a bottom view of the housing as shown in FIGURE 3.

We claim:

The ornamental design for a rotary mower housing, substantially as shown.
